H. A. BOWER.

PRACTICE DRUM.

APPLICATION FILED FEB. 27, 1919.

1,346,588.

Patented July 13, 1920.

By Henry L. Thomson

Attorney

UNITED STATES PATENT OFFICE.

HARRY A. BOWER, OF BOSTON, MASSACHUSETTS.

PRACTICE-DRUM.

1,346,588.

Specification of Letters Patent.

Patented July 13, 1920.

Application filed February 27, 1919. Serial No. 279,575.

To all whom it may concern:

Be it known that I, HARRY A. BOWER, a citizen of the United States of America, residing at Boston, in the county of Suffolk and State of Massachusetts, have invented new and useful Improvements in Practice-Drums, of which the following is a specification.

This invention relates to music and particularly to drums, said invention having for its object the provision of a practice drum or a device which will give practically the same rebound to the drum sticks without being unduly noisy, thus making it possible for a performer to practise without annoying the occupants of adjacent rooms or buildings.

A further object of this invention is to produce an instrument in which the vibratory action of one member is such as to enable the performer to practise the roll and other movements commonly practised in drumming, so that such a performer will gain the skill and experience necessary for him to transfer to a drum and perform in practically the same manner as he did in practice, and acquire satisfactory results.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a plan view of an instrument embodying the invention;

Fig. 2 illustrates a view in elevation thereof; and

Fig. 3 illustrates a sectional view.

In these drawings 5 denotes a base, preferably of rather dense or hard wood having apertures 6 therein for the reception of lacing ribbon 7, which lacing ribbon is utilized for binding the parts of the device and holding them on the base, as will presently appear.

Superimposed on the base is a layer of resilient sound insulating material 7^a, such as felt, the said insulating material constituting a support or cushion for what might be termed a sounding board 8 which, in the

present embodiment of the invention consists of a rather thin plate which may be formed of gutta percha, whalebone, or a composition, such as papier mâché, fiber-board, or any relatively stiff yet flexible or vibratory material which will be affected by the impact of the drum sticks similar to the effect occasioned by said sticks when they impact drum heads.

The said plate 8 is preferably made from material which has been convexed in the course of or after its manufacture as it has been found that such form increases its vibratory action. The convex form of plate 8 also produces a more satisfactory sound effect and also more exactly communicates to the fingers a sense of feeling termed "stick sense" by those acquainted with the art of drumming.

Superimposed on the plate 8 is a layer of felt 9 for the purpose of serving as a supplementary vibratory member or "mute" when it is desired to reduce the sound produced by practising on the sounding board 8.

The plate 8 has apertures 10 alining with the apertures 6 of the base and the supplementary vibratory member 9 has apertures 11 at one end which aline with apertures in the base and plate so that the lacing ribbon 7 may be passed through the apertures for the purpose of holding all the parts in assembled relation to one another and the said lacing ribbon may have its ends anchored to a stud or pin 12 rising from the base. The lacing ribbon 7 passes on each side of the cushion and prevents lateral displacement of the cushion and the relation of parts is indicated and well shown on the drawing.

A binding 13 is applied to the base and extends over an end of the cushion, plate and pad to give a finished appearance, said binding being secured to the base by fastenings 14, such as tacks or the like.

The cost of manufacture of this device is comparatively small and the instrument presents a neat appearance and the lacing ribbon or that portion of it which extends under the base constitutes a support so that the base can be supported on articles of furniture without liability of scratching or marring the same.

I claim—

1. In a practice drum, a base, a cushion thereon, a vibratory member entirely supported by the cushion, a sound reducing

member superimposed on said vibratory member, and means for securing the parts in assembled relation to one another.

2. In a practice drum, a base, a cushion thereon, a vibratory member entirely supported by the cushion, said vibratory member being convex in cross-section, a sound reducing member superimposed on the vibratory member, and means for securing the parts in assembled relation to one another.

3. A device of the class described, comprising a base, a sounding-board spaced therefrom, and cushioning means between said base and sounding board, said cushioning means entirely supporting the sounding-board.

4. A device of the class described, comprising a base, a sounding-board spaced from said base, cushioning means between

said base and sounding-board, said cushioning means entirely supporting the sounding-board, and means for securing the parts in assembled relation to one another. 20

5. In a practice drum, a base, a cushion thereon, a plate supported by said cushion, 25 and means for securing the parts in assembled relation to one another.

6. In a practice drum, a base, a cushion thereon, a plate supported by the cushion, said plate being convexed in cross-section, 30 and means for securing the parts in assembled relation to one another.

In testimony whereof I affix my signature in presence of two witnesses.

HARRY A. BOWER.
